UNITED STATES PATENT OFFICE.

GARFIELD H. BRETSCH, OF SAN DIEGO, CALIFORNIA.

DENTAL INSTRUMENT.

1,152,281.

Specification of Letters Patent. Patented Aug. 31, 1915.

Application filed December 13, 1913. Serial No. 806,530.

To all whom it may concern:

Be it known that I, GARFIELD H. BRETSCH, a citizen of the United States, residing at San Diego, in the county of San Diego and 5 State of California, have invented certain new and useful Improvements in Dental Instruments; and I do hereby declare the following to be a full, clear, and exact description of the invention, such as will enable others skilled in the art to which it 10 pertains to make and use the same.

My invention relates to new and useful improvements in dental instruments, more particularly to an instrument for sharpening the exposed ends of pins carried by a porcelain facing or tooth used in dentistry in the manufacture of crown and bridge work.

An important object of my invention is to 20 provide a tool such as above described that is adapted to be rotatably connected with a dental engine or like machine and is particularly designed for sharpening the ends of pins carried by porcelain facings or 25 teeth that are adapted to be backed with platinum or gold plates.

Heretofore in dentistry it has been the custom to punch holes with a plate punch through a backing plate of gold or platinum 30 for a porcelain facing or tooth in the construction of crowns or bridge work for teeth and to insert the facing pins through the openings in the backing plate.

My invention aims to provide a simple 35 and reliable tool whereby the pins carried by the porcelain facings or teeth may be readily and evenly sharpened whereby they may be inserted through the usual gold or platinum backing plates and provide a tight connection 40 where inserted through the backing plates as heretofore in having holes punched through the backing plates and the pins inserted therethrough, a tight connection was not provided.

45 A still further object of my invention is to provide a device such as above described which is simple as to construction and arrangement of parts may be cheaply manufactured and is capable of being readily attached to dental engines or like machines.

The above and additional objects are accomplished by such means as are illustrated in the accompanying drawings, described in the following specification and then more

particularly pointed out in the claims which 55 are appended hereto and form a part of this application.

With reference to the drawings, wherein I have illustrated the preferred embodiment 60 of my invention as it is reduced to practice, 65 throughout the several views of which, similar reference numerals designate corresponding parts: Figure 1 is a top plan view of my device as it would appear in assembled position, Fig. 2 is a longitudinal sectional view 70 taken on line 2—2 of Fig. 1 illustrating the relative positions of the several parts of my device when in assembled position, Fig. 3 is a cross sectional view taken on line 3—3 of Fig. 2, and Fig. 4 is a cross sectional view 75 taken on line 4—4 of Fig. 2.

Referring now more particularly to the drawings forming a part of this specification and in which like numerals are employed to designate corresponding parts, the 75 numeral 1 designates as an entirety a shank of a cylindrical form that is adapted for operative connection with a chuck not shown of the usual dental machine or lathe. This shank 1 is provided with an enlarged cylindrical body portion 2 at one terminal that is provided adjacent with screw threads 3 for a purpose which will be later more fully disclosed.

Formed within the enlarged portion 2 of 85 the shank 1 is a longitudinally extending groove or slot 4 that terminates adjacent the outer terminal of the portion 2 in a restricted annular opening 5 that is adapted to have the pins carried by the porcelain facings or teeth inserted therein to be sharpened after a manner which will be later more fully described. The free end of the enlarged portion 2 is reduced as at 6 to facilitate the positioning of the tool for sharpening 90 the pins as hereinbefore described when the pins are arranged in close relation to each other.

Mounted within the groove 4 is a sharpening member 7 that is approximately rectangular in shape and constructed of some suitable hardened material. This sharpening member 7 is reduced at its forward terminal upon one side thereof as at 8 and provided upon the opposite side adjacent the 100 forward end thereof with an inclined face and cutting edge 9 extending angularly with 105 relation to the opening 5 in the end of the

portion 2 and past the center of the opening 5, whereby the pins carried by the porcelain plates or teeth may be inserted within the opening 5 and readily sharpened by engagement with the inclined face 9 of the sharpening member 7. The reduced portion 8 is shaped to conform to the shape of the reduced portion 6 of the enlarged portion 2.

Mounted upon the enlarged portion 2 is a cylindrical sleeve or collar 10 provided at one terminal with internal screw threads adapted to engage the screw threads 3 on the enlarged portion 2 whereby the sleeve is held in engagement with the sharpening member 7 and serves to hold it in place within the groove or recess 4 as will be clearly seen with reference to Fig. 2 in the drawings.

The sleeve 10 is provided adjacent its internally screw threaded terminal with a pair of annular spaced gripping ribs 11 that may be knurled to provide for a better gripping engagement of a suitable tool or fingers when it is desired to disassemble or assemble the tool.

25 The cylindrical sleeve 10 is, when secured upon the enlarged portion 2 after the manner hereinbefore described, spaced at its outer end with relation to the outer reduced portion 6 of the enlarged portion 2 for a purpose which will be later more fully described.

30 Formed integral with the sharpening member 7 adjacent the outer longitudinal edge thereof and at a point near the reduced portion 8 thereof is an upstanding lug 12. This lug 12 is adapted for engagement with the adjacent edge of the cylindrical sleeve 10 and serves to hold the sharpening member 7 in the desired position within the recess or groove 4 of the enlarged portion 2 of the shank 1.

Having fully described the structural details of my invention it now remains to take up the description of the operation which 45 may be briefly outlined as follows: The shank 1 is operatively connected with a suitable dental lathe or like machine such as commonly employed by dentists for operating their various tools and provision for the 50 rotation of the tool is had. To sharpen the pins carried by the facings of porcelain or teeth carrying pins the reduced portion 6 of the enlarged portion 2 of the shank 1 is placed so that one of the pins is disposed 55 within the opening 5 and in a position for engagement with the inclined face and cutting edge 9 of the sharpening member 7.

Upon the rotation of the enlarged portion 2 it will be readily seen, that the ends of 60 the pins after being inserted within the opening 5 and disposed in engagement with the cutting edge 9 of the member 7 are readily sharpened. The points produced on the ends of the pins by the tool as herein- 65 before described is a smooth conical one that

permits the piercing of a backing plate for facings in a reliable and efficient manner so as to insure a perfect connection or joint as this is a desirable point in the construction of dental crowns and bridge work for the 70 teeth.

It will be apparent that without the lug 12 constant use of the device would result in the shaking loose of the cutting element 7 since it engages at two points the holder 75 therefor. By tightening or turning the sleeve 10 it will be seen that the cutting element 7 will be securely clamped in the holder since the lug 12 engages said sleeve.

It is apparent with reference to the foregoing description and accompanying drawings that there has been provided a dental instrument which will permit the sharpening of pins carried upon porcelain facings or teeth in a reliable and expeditious manner and while the tool is designed particularly for use in connection with the purpose above mentioned it may be used to sharpen the points of various instruments employed by dentists as well as for the primary purpose intended.

In reduction to practice, I have found that the form of my invention, illustrated in the drawings and referred to in the above description, as the preferred embodiment, 95 is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended 100 claims.

105 What is claimed is:—

1. A dental instrument comprising a cylindrical body portion having a longitudinal groove in one side thereof and an opening in its outer end communicating with said groove, a sharpening member mounted within said groove and engaging the ends thereof at its ends, said sharpening member being spaced its entire length from one side of the groove and having an inclined face opposite to said opening, an outstanding lug carried by said sharpening member, a sleeve adjustably mounted upon the body portion and receiving the greater part of said sharpening member and engaging the 115 lug thereon.

2. A dental instrument comprising a cylindrical body portion having a shank extending from one end thereof and an opening in the other end thereof, said body portion having a longitudinal groove in one side thereof and communicating with said opening, a sharpening member mounted within said groove, said body portion being 125 screw threaded adjacent to its inner end, a 130

cylindrical internally screw threaded sleeve mounted upon the body portion and receiving the greater part of said sharpening member, said sharpening member engaging 5 at its ends the ends of said groove and having the face thereof which is opposite to said opening inclined and arranged for engagement with objects inserted in said opening and a lug carried by said sharpening mem-

ber and engaging the outer end of said 10 sleeve.

In testimony whereof I affix my signature in presence of two witnesses.

GARFIELD H. BRETSCH.
